UNITED STATES PATENT OFFICE.

GEORGE M. WILEY, OF LOS ANGELES, CALIFORNIA.

DISPLAY APPARATUS.

1,271,817.

Specification of Letters Patent.

Patented July 9, 1918.

Application filed November 19, 1917. Serial No. 202,865.

To all whom it may concern:

Be it known that I, GEORGE M. WILEY, a citizen of the United States, residing at Los Angeles, in the county of Los Angeles and 5 State of California, have invented a certain new and useful Display Apparatus, of which the following is a specification.

My invention relates to a device for forming upon a suitable background, images, 10 pictures, signs, words, legends or in fact designs or outlines of any form or character having either an educational or artistic merit, coupled with interest in the manner of display, or a commercial value that will 15 stimulate attraction and at the same time advertise certain grades or classes of merchantable goods.

Objects of this invention are to provide a device in which an outline or design of a 20 definite artistic or exhibitory nature may be cast or formed upon a contrasting canvas or screen without the cause of the formation being or becoming known to the spectators, and to provide a device of simple and eco- 25 nomical construction for carrying out the objects enumerated.

A further object of this invention is to provide a display device in which a variety of subjects may be successfully exhibited 30 and such exhibition controlled automatically.

Other objects will appear from the subjoined specification in connection with the accompanying drawing, illustrating a form 35 of apparatus for carrying out this invention.

In the drawing—

Figure 1 is a front elevation, partly 40 broken to show the trough for the flakes and the distributing means for the air.

Fig. 2 is an elevation showing the various parts broken to illustrate interior construction, otherwise hidden.

Fig. 3 is a section on line 3—3 Fig. 2.

Fig. 4 is a rear elevation, and

Fig. 5 is a perspective segregated view of the associated means for effecting distribution of the air.

My invention consists of a means, pref- 50 erably pneumatic, for agitating or disseminating within a definite area a mass of flakes, flaked material, shreds or chips, or other light particles that may readily be carried and flurried by air currents, and causing 55 a portion of the whirled mass to lodge or

accumulate and be held at definite points on and within definite areas of a screen or canvas to form a predetermined outline or an *en masse* collection for pictorial or other representation, as desired.

To this end I provide a suitable section 1, of any design or construction, having a transparent front 2, as of glass, and a box portion 3 at the bottom thereof, which box is open at the top and communicates with 60 the space formed by the section 1. Within such box is disposed a trough 4, circular in longitudinal and vertical cross section, for a mass A of flakes, shreds, or fragments of any light material, which may be plain, colored or mixed, as desired, for producing the 65 most attractive effect.

Centrally of said trough 4, is an air distributor 5, consisting in the instance shown in Fig. 5, of a T 6, divided by a central partition 7, into two passageways 8 and 9; the branch 10, of said T extending through the wall 11, of said box 3. In air tight engagement with the end of said branch 10, may be a substantially rectangular conduit 70 12, having two lower passageways 13 and 14, which are arranged to register with the passageways 8 and 9, of said branch, and an upper passageway 15, which is arranged to register with a vertical air duct 16, disposed 75 above said T. The conduit 12, is fitted into the outlet pipe 17, of a blower 18, or other 80 current producing means.

Such air distributor 5, serves to divide the air into separate streams, whereby an accumulation of the flakes or shreds at any one point in the section 1, is prevented and a 85 perfect agitation brought about.

Onto the rear of the section 1, is removably fastened a section 1'; forming with the 90 section an air tight inclosure.

Within said section is a plurality of horizontal strips or riffles 19, on the front of which is fastened a backing or support 20, consisting preferably of any suitable reticulate fabric or porous material, for a screen 21, of rubber, wood or paper, provided with openings or perforations 22, forming an 100 outline or figure. Such openings or perforations may represent artistic shapes or figures, or other subjects designed for exhibition, and may be so arranged and distributed over the area of the screen that they 105 collectively form a pictorial or other group, while retaining, when separately or succes- 110

sively exhibited, as hereinafter appearing, their individual value and artistic appearance.

The screen 21, and backing or support 20, are glued or otherwise fastened to the front of the strips or ruffles 19, which divide the screen 21, into a plurality of zones 23, in some of which certain outlines or designs are contained, and in others of which certain other different outlines or designs may be represented by the perforations or openings 22.

Within the section 1, and affixed to the back of said strips or ruffles 19, is a cover 24; the space between such cover and the screen 21, being, divided into a plurality of compartments 25, having no communication with each other.

The cover 24, is provided with two rows 26 and 27, of alternate openings, divided by a vertical partition 28, which also divides the space in said section 1' in back of the cover 24, into the two chambers 29 and 30.

The rows 26 and 27, respectively, of alternate openings, provide passageways for the air from the front of the screen 21, to the chambers 29 and 30, respectively, the circulation of air for effecting the exhibition of outlines or designs on alternate zones of the screen, 21, in succession, being controlled by any suitable mechanism, such as presently detailed.

The bottom of the section 1' on each side of the partition 28, is provided with an opening 31 and 32, registering with openings 33 and 34, in the top of a closed receptacle 35, which is integral with the section 1', and is divided into two compartments by a partition 36; the inner wall 37, of said receptacle 35, is provided on each side of the partition 36, with an air outlet 38 and 39, controlled by valves 40 and 41, respectively, which are arranged to be operated and held opened alternately by a plurality of cams 42 and 43, mounted on a shaft 44, carried in suitable supports 45, and driven from the shaft 46 of the blower 18, which in turn is driven by any source of power not shown.

The currents of air caused by the blower 18, and distributor 5, whirling in various circulatory directions, produces a dissemination of the flakes or shreds A, in the section 1. On such zones only of the screen 21, where the air currents pass through the perforations in the screen, and the respective row of openings in the cover 24, an accumulation of the flakes will occur, and such accumulation will be of a design or outline exactly in accordance with the design or outline formed by the perforations or openings in the screen.

Obviously such passage of air cannot occur until the valves 40 and 41 are operated, and in order that the exhibition may be made in accordance with a predetermined

design, the valves are operated alternately, first to produce upon the screen, as shown in Fig. 1, the first, third and fifth lines, and second, to produce the second, fourth and sixth lines. Thus, referring to Fig. 4, when the cam 42, has opened the valve 40, the air circulates through the perforations in those zones of the screen, having corresponding outlets 26, in the cover 24, the air passing out through the air outlet 38. The valve 41, is held closed by air pressure from the inside until opened by the cam 43.

Those flakes that are not arrested by the air passing through the perforations, are continuously whirled about in a continuous stream. When the air currents cease, the flakes will gravitate slowly to the trough. It will be apparent that any number of zones, valves and other parts, to give a greater variety of display, is fully within the scope of the invention.

What I claim is:

1. A display apparatus comprising an inclosure, a screen within said inclosure, having cut-out portions, and dividing said inclosure into a front and rear compartment, a mass of flaked material in said front compartment, means to supply air currents to said front compartment to agitate said mass of flaked material and cause an accumulation of said material at points on said screen where the cut-out portions occur, means dividing said screen into a plurality of zones, and means to control the circulation of the air currents to cause successively an accumulation of the flaked material on alternate zones of said screen.

2. A display apparatus comprising an inclosure, a screen within said inclosure having cut-out portions, means dividing said screen into a plurality of zones, a mass of flaked material in front of said screen, means to produce air currents to agitate said mass, and means to control successively the circulation of air currents through alternate zones of said screen to cause an accumulation of said material in those zones only through which the air currents circulate.

3. A display apparatus comprising an inclosure, a screen within said inclosure having cut-out portions, a mass of flaked material, means to produce air currents to agitate material, and means to control the circulation of air through certain of said cut-out portions to cause an accumulation of the material at points only where the air currents may pass through.

4. A display apparatus comprising an inclosure, a screen therein having cut-out portions, a mass of flaked material, means to produce air currents to agitate the material, and means to control the circulation of air alternately through said cut-out portions to cause an alternate accumulation of the

material on said screen and at points only where the air currents may pass through.

5. A display apparatus comprising an inclosure, a plurality of strips therein, a screen fastened on the front of said strips, and having cut-out portions divided by said strips, a cover on the back of said strips and provided with a plurality of rows of alternately arranged openings, said screen 10 and cover dividing said inclosure into a front and a rear compartment, a mass of flaked material in said front compartment, means to produce air currents within the front compartment, means in said rear compartment forming separate air circulating divisions corresponding in number to the rows of openings in said cover, and means to control the circulation of air alternately through the cut-out portions in said screen 15 20 and said divisions to cause an accumulation of said material at points only on said screen where the air may pass through.

6. A display device comprising an inclosure, a plurality of strips in said inclosure, a screen fastened on the front of said strips 25

and having cut-out portions, said strips dividing said screen into a plurality of zones, a cover fastened on the back of said strips, said screen and cover dividing said inclosure into a front and rear compartment, the rear 30 compartment divided into a plurality of chambers, having outlets, said cover having a plurality of rows of alternate openings providing communication between the front compartment and the chambers in the rear 35 40 compartment, a mass of flaked material in said front compartment, means to produce air currents within said front compartment, and means to control alternately the circulation of air from the front compartment to the chambers in said rear compartment, whereby to cause an accumulation of the material on alternate zones of said screen successively.

In testimony whereof I affix my signature 45 in the presence of two witnesses.

GEORGE M. WILEY.
